LOCK

Franklin H. Harp, Indianapolis, Ind., assignor to Frank E. Best, Inc., Seattle, Wash., a corporation of Washington

Original application April 17, 1933, Serial No. 666,520, now Patent No. 2,138,856, dated December 6, 1938. Divided and this application December 5, 1938, Serial No. 243,970

6 Claims. (Cl. 70—148)

This invention relates to locks and this application is a division of my application, Serial No. 666,520, filed April 17, 1933, Patent No. 2,138,856, issued December 6, 1938.

The general object of my invention is to improve the construction of locks generally, and to render the same more efficient and reliable in operation.

The invention, as herein disclosed, is embodied in a door lock of the form commonly termed a "unit lock," but it will be understood that the invention is not to be restricted to so called "unit locks," but that many features of the same are applicable to locks of other types.

An object of the invention is to provide novel and efficient means for locking one or both knob shanks against turning, said means being selective whereby it may be used to lock one knob shank and leave the other free to rotate or to lock both knob shanks or to lock certain mechanism which will prevent retraction of the bolt by a key, and at the same time lock one or both knobs as may be desired. This knob shank locking means may be controlled by a single small turn knob operable from the inner side of the door or in some instances by either one or two turn knobs which are positioned on opposite sides of a door. These objects may be accomplished by having two locking slides which may be movable simultaneously in opposite directions, or which may be movable independently of each other.

Another object is to provide a lock which may readily be installed on a right or left hand door.

Other and more specific objects of the invention will be apparent from the following description taken in connection with the accompanying drawings.

In the drawings Fig. 1 is an elevation with certain cover plates and knob parts removed, of a lock constructed in accordance with my invention.

Fig. 2 is a sectional view of said lock substantially on broken line 2—2 of Fig. 1, parts being shown in elevation.

Fig. 3 is a detached view partly in section and partly in elevation through a knob lock mechanism embodied in this lock, showing parts of the throw mechanism connected therewith.

Fig. 4 is a detached view partly in elevation and partly in section showing parts of the throw mechanism in slightly spaced apart relation.

Figs. 5 and 6 are diagrammatic elevations on a larger scale substantially on broken line 5—5 of Fig. 4, of the throw parts shown in Figs. 3 and

4, showing different operative positions of the several parts.

Fig. 7 is a fragmentary view partly in section and partly in elevation illustrating the operation of a bolt member embodied in this lock, the bolt member being shown in fully retracted position and a bolt blocking member being shown, partly by dotted lines in a blocking position.

Fig. 8 is a fragmentary view similar to Fig. 7, except that the bolt member is illustrated as blocked by the blocking member.

Fig. 9 is a detached elevation showing an alternative form of locking slide which cooperates with the bolt blocking member.

Fig. 10 is an elevation similar to Fig. 9, showing another alternative type of locking slide and an alternative type of blocking member.

Fig. 11 is a detached plan view showing the use of two locking slides arranged to be moved simultaneously in opposite directions by a single actuating member.

Fig. 12 is a detached plan view illustrating an alternative type of slide operating means.

Fig. 13 illustrates another alternative type of slide operating means.

Figs. 14 and 15 are detached plan views of two types of bolt retracting members embodied in this lock.

Fig. 16 is a detached view in elevation showing two abutting lock spindles of a type which may be used when a separate lock is provided in each knob of the lock and when an independent throw is controlled by each lock.

Fig. 17 is a detached elevation showing two overlapped lock spindles.

Fig. 18 is a sectional view through a knob shank illustrating the manner of providing an angularly offset hole for cooperation with a locking pin whereby the bolt may be held retracted.

Figs. 19 and 20 are detached elevations respectively of two tubular supporting members for the knob shanks.

Fig. 21 is a detached plan view of a member which is used to secure the knob shanks in assembled relation in the lock.

Fig. 22 is a detached view partly in elevation and partly in section showing two thumb turns on opposite sides of a lock each operating a separate locking slide.

Like reference numerals designate like parts throughout the several views.

Referring to Figs. 1 and 2, I show a knob which embodies a knob cylinder or lock case 20 recessed as at 21 to receive a primary lock 22, preferably of pin tumbler type. The cylinder 20

forms a body about which the knob is built. The knob may consist of an inner shell portion 23 and an outer shell portion 24. The outer shell portion 24 preferably forms the outer end and peripheral portion of the knob and overlies a portion of the end of the cylinder 20 and has an inwardly protruding annular rib 25 fitting over the end of the cylinder 20, said rib serving as a means for correctly positioning the shells 10 relative to the outer end of the cylinder. The end of the outer shell is further cut away as at 26, to afford access to the end of the lock. The inner shell portion 23 is partially disposed within the outer portion and is frictionally engaged by the outer shell portion so that the shell members will turn together as a unit and said inner shell portion has a neck 27 which is press fitted tightly onto the cylinder member 29 and further has an inwardly extending flange portion 28 which overlaps the marginal part of one side of an external annular flange 30 which is integral with or otherwise fixedly secured to a knob shank 31. The flange 28 of the inner shell 23 is preferably secured to knob shank 25 flange 30 by a shear pin 32, so that it will shear off if excessive torque is exerted on the knob. The knob shank 31 is arranged to retract a lock bolt as hereinafter described, when it is turned.

The primary lock 22 which is disposed in 30 the cylinder 20 may be of a well known pin tumbler type. The cylinder 20 has a flange portion 51 near its inner end which separates the compartment in which the primary lock 22 is disposed from a compartment 52 in which 35 throw mechanism is positioned. This throw mechanism embodies a throw disc 53 having two throw pins 54 rigid therewith and protruding telescopically into the primary lock 22 whereby the throw disc 53 may be turned by the 40 insertion of a key in the primary lock. A retainer plate 55 secured to the housing flange 51 retains the disc 53 in place and has an opening 56 therein to afford clearance for the two throw pins 54. The disc 53 has a crank 57 protruding from the inner face thereof and extending through an elongated hole 58 in one end of a throw link 60. The other end of the throw link 60 has a hole 61 which fits over a throw 45 lever pin 62 on a throw lever 63 which is secured to the end of a throw spindle 64, preferably of 50 square cross section, by which latch mechanism of a form hereinafter described is operated. The throw link 60 is thus positioned so that it operates freely between the throw lever 63 and the 55 throw disc 53. When the throw disc 53 is in the normal inoperative position which it must occupy at all times when the key is removed from the lock the crank pin 57 on said throw disc 53 will be in axial alignment with the throw spindle 64 and both will coincide with the common axis of the knob spindle and the knob. In the event the shear pin 32 is sheared off and the knob is turned without turning the knob shank, when the throw pin 57 and throw spindle 60 are thus positioned with their axis common 60 to the axis of the knob and knob shank, the throw disc 53 will likewise be free to rotate on this common axis but the knob spindle 64 will not be rotated and consequently the latch mechanism will not be retracted. This allows the shear pin 32 of a knob to be sheared off and the knob to be rotated by an unauthorized person when the latch mechanism is locked without operating the latch mechanism or damaging any part of the same, the shear means and

throw means thus cooperating to prevent the lock from being opened or seriously damaged by persons seeking to force the lock.

If the throw disc is rotated by insertion of the proper key in the lock the crank pin 57 moving around on the arc of a circle, see Figs. 5 and 6, will exert a thrust on the link 60, which thrust will be transmitted to the throw lever pin 62 thus moving the throw lever 63 and turning the throw spindle 64. The turning of 10 the throw spindle 64 may retract a latch bolt in a manner hereinafter described. The elongation of the hole 58 in the throw link 60 affords some lost motion between the crank pin 57 and the throw link 60 and insures that the thrust 15 exerted on the throw link will be sufficiently off center to impart a torque to the spindle 64. The oversize of the hole 58 of the throw link 60 also takes care of any inaccuracy of the positioning of the throw lever pin 57 with respect to the 20 axis of the knob and the knob shank and makes it possible to rotate the knob without turning the throw spindle even though the throw lever pin is positioned slightly off center relative to the axis of the knob and knob shank. 25

A knob-shank bearing-tube 65, Figs. 1, 2, 19 and 20, is provided for the reception of the knob shanks 31. This bearing tube 65 is supported in a bearing tube holder 66 which is secured, as by screws 67 to a lock 68. A set screw 70 serves 30 to clamp the bearing tube 65 to the bearing tube holder 66. The bearing tube 65 is cut away as at 71 to afford clearance for the operation of a plurality of throw members 72, 73 and 74. The two throw members 72 and 73 are shaped to fit within counterbored and notched portions 75 in the ends of the knob shanks 31 whereby they will be moved rotatively by the turning of these knob shanks. These two throw members are hereinafter termed knob throws. When a primary lock 22 is provided in one knob only, as illustrated in Fig. 2, then only one lock throw 14 is provided and this lock throw is operated by the single spindle 64. In some instances where a primary lock 22 is provided in each knob two overlapped spindles 76 and 77 of a form shown in Fig. 17, may be used said spindles rotating together as a unit and operating a single lock throw and being controlled by either of said locks, the throw mechanism, shown in Figs. 3 and 4, which connects the spindles with the locks making it possible to operate the spindles 76 and 77 by the insertion of a key in either lock without in any way affecting the other lock. In this type of mechanism each primary lock 22 is capable of performing the same function as respects the latch mechanism. Suitable springs, hereinafter described always tend to return the locking spindles to normal position when they are released and the primary pin tumbler locks require that the key must always be brought back to the same position before it can be withdrawn from the lock; this always insures correct positioning of the primary lock throw parts and the spindles when the lock is not in actual use. 45 The several spindles may be of square cross section, the openings 31' in the knob shanks may be circular, the openings 72' and 73' in the hub portions of the knob throws 72 and 73 may also be circular so that the knob and knob shanks are not rotatively connected with the spindles. The opening 74' in the lock throw 74 may be square whereby the lock throw 74 will be controlled by the turning of the spindle or spindles which pass therethrough. In some in- 50 55 60 65 70 75 80 85 90 95 100

stances it may be desirable to have a primary lock 22 in each knob and to have each of these primary locks operate a different lock throw member, Fig. 16, whereby each primary lock may exercise a different control over the latch mechanism and whereby the latch mechanism controlled by one of these primary locks can not be operated by the other primary lock. In this instance I replace the medial lock throw member 74 by two lock throw members 80 and 81, Fig. 16, and provide two shorter shanks 82 and 83 which protrude respectively into the lock throw members 80 and 81 and may substantially abut against each other end to end. This provides a separate control by the primary lock in each knob, making it possible to render either lock ineffective to retract the latch bolt.

Other variations of the throw members 72, 73, 74, 80 and 81, may be provided, as for instance, these throws may all be secured together or may all be made in one piece in certain types of locks where no key operated primary lock mechanism is used and where it is desired to rigidly connect the two door knobs together.

Two pairs of slots 84, Fig. 19, are provided in the bearing tube 65 and extend partially around said bearing tube 65 adjacent opposite ends of the cut away portions 71 for the reception of flat prongs 85 on U shaped clips 86, Fig. 21, by which the knob shanks 31 are secured in assembled relation within the bearing tube 65, the said prongs 85 fitting within annular grooves 87 in the knob shanks. These clips form a very efficient means for holding the knob shanks and permit a very quick and easy assembly or disassembly without the use of special tools. A quick and easily removable slide plate 88 forms a closure at the rear end of the lock case. This slide plate also retains the clips 86 in proper position when the lock is assembled.

The bearing tube holder 66 has two arms 69 protruding from the upper end thereof at diametrically opposite locations and positioned in contact with the sides of the bearing tube. These arms 69 each have a plurality of spaced apart holes 90 therein and the bearing tube is correspondingly provided with holes 91 which register with the holes in the arms 69. The knob shanks 31 are also provided with holes 92 which register with the holes in the arms 69 and bearing tube 65. These several holes constitute a part of the means for locking the knob shanks 31 against turning. Only one set of these holes for each knob shank need be occupied by pins for locking the knob shanks. The elements which lock into these holes 90, 91, 92, are in the nature of pin means 93 in a locking slide 94. This locking slide may be varied in form and in some instances two of these slides may be used as hereinafter set forth. The slide shown in Figs. 1, 2, and 7 may comprise a flat face portion 95 to which the pin or pins 93 are secured and a flat shank portion 96 positioned at right angles to the face portion 95 and guided for sliding movement in notches 97 which are provided in guide members 98 and 99, Fig. 8, said guide members being fixedly secured to the lock case 68. A slide retainer bracket 100, is provided for holding the slide shank 96 down. The top edge of the slide shank 96 has a shoulder 101 thereon for engagement with the forward edge of the slide retainer bracket 100, whereby rearward movement of said slide is limited and a notch 102, is provided in the top edge of said slide shank just forward of the shoulder 101, for the reception of an arm 103, on a thumb

operated spindle 104. An upright post 105, having a pin 106, on the top end thereof forms a positioning and bearing means for the spindle 104, and said spindle 104 is further supported for rotation within the cover 107, of the lock case 68. The lower edge of the slide shank 96 has two or more notches 108 provided therein for engagement by a V shaped element 109 provided on a flat spring 110, see Figs. 2 and 7. Obviously oscillating movement of the thumb turn spindle 104 will move the slide back and forth and cause the pins 93 to enter or to be withdrawn from the holes 92 in the knob shanks 31 thus locking or unlocking the knobs as respects turning movement thereof. If it is desired to provide for locking only one knob then only one pin 93 is provided on the plate 95. If both knobs are to be locked then two pins 93 are provided as shown on the slide face 95 in Fig. 8, so that pins will enter holes in both knob shanks. The locking of the inside knob along with the outside knob is particularly desirable in the case of some doors. Where the inside knob is thus locked it is desirable to operate the locking slides by means of a key or to lock the turn knobs so that they can not be moved to released position until after the door has been opened by a key. If it is desired to prevent operation of the lock by a proper key then an additional pin 93', Fig. 10, may be provided for entrance into a notch 111, in the hub portion of the key throw 74, see Fig. 15. Also in instances where two key throws 80 and 81, Fig. 16, are used this pin may enter corresponding notches 112 of both of said key throws to prevent operation by the primary lock mechanism in either knob by the use of a proper key.

In Fig. 11, I have shown two locking slides 113 and 114 guided in the guide members 98 and 99 in spaced apart relation, one on each side of a turn knob shank 115 and engaged by oppositely extending arms 116 and 117 on the turn knob shank 115 whereby said two slides will always be moved in opposite directions by turning movement of the turn knob shank 115. The slides 113 and 114 each have front plates 118 thereon and each front plate may have one or more pins 93. The pin carrying portion 118 of the plate 114 is offset whereby it will clear the front portion 118 of the other locking slide. The pin 95 of one slide may be arranged to engage with one knob shank while the pin 93 of the other slide may be arranged to engage with the other knob shank. This makes it possible to leave both knob shanks unlocked or to lock either knob shank and leave the other knob shank unlocked. When this construction is used one turn knob 119 may be employed, or two turn knobs 119 may be provided, one on each side of the door. In this instance the thumb knob or knobs may have three positions namely; one position for locking one knob, another position for locking the other knob, and a third or neutral position in which both door knobs are unlocked. These three positions are secured and definitely predetermined by providing in the bottom edges of the slides, see Fig. 9, three notches 121 which are arranged to be engaged by the inverted V shaped detent 109 on the spring 110, one of said notches determining each of the positions above mentioned.

An indicator 161 may be secured by a pivot 162 to the bracket member 98 and engaged by an inclined front edge 163 on the locking slide 94. When locking slide 94 is in locking position the indicator is moved out through a hole 164 in the lock case, thus indicating visibly that the lock is 75

in a locked condition. When the locking slide 94 is retracted a spring 165 retracts the indicator 161 and causes it to disappear inside of the lock case.

5 If the movement of the locking slides, as for instance, slides 113 and 114, is to be controlled by the primary lock or locks then a throw member 122 of the form shown in Fig. 12, is preferably provided for use in cooperation with the lock 10 spindles. This throw 122 has two arcuate recesses 123 for the reception of disc like portions 124, of links 125. The links 125 have hook portions 126 on the outer ends thereof for engagement within holes 127 in the face portions 118 of the locking 15 slides 113 and 114. The hook portions 126 are shaped so as to afford a limited amount of lost motion between the links 125 and the slides and this lost motion always allows the throw 122 to return to its normal inoperative position without 20 disengaging the locking slides after said locking slides have been moved into a locking position. If the two slides 113 and 114 are interconnected by the member 115—116—117 then only one of the links 125 need be used but if said two locking 25 slides are not so interconnected then two links 125 will be used. If only one locking slide is to be moved then obviously only one link 125 will be used. If two locking slides are to be independently controlled then two throws 122 are provided, each throw is connected by one link 125 with one locking slide and the locking slides are not interconnected.

Another mechanism for controlling one or both locking slides 113 and 114 by means of the lock 30 throw 122 is illustrated in Fig. 13, in which I provide an extension lug 129 on each slide each extension lug 129 being positioned for engagement with an arm 128 on the throw member 122. Said extension lugs are preferably used in connection with the slide interconnecting member 115—116—117. This mechanism has less lost motion than the slide operating mechanism shown in Fig. 12.

The lock case 68 is provided with a face plate 45 130 having an opening 131 for operation of a bolt member 132 of conventional hollow type which is mounted on a pivot 133. A bolt trip 134 Figs. 1, 7 and 8 is secured within the bolt member 132 by a pivot 135 and has a catch portion 136 which projects out of the bolt member 50 into the lock housing. A torsion spring 137 urges the bolt trip 134 into the position shown in Fig. 2. This bolt trip 134 has another pivot 138 which is connected with a sub-tongue member 139 which extends into the lock case and rests upon the bracket 100. The sub-tongue member 139 has a slot 140 engaged by a finger 141 on a tongue plate 142 which is guided for sliding movement in the lock case. A spring 145 55 engages with a lug 146 on the tongue plate 142 and urges said tongue plate 142 toward the forward end of the lock housing. The central portion of the tongue plate 142 is cut away for clearance purposes and two wings 145 are provided on the rear end of the tongue plate for engagement 60 with the several throw members which are operated either by turning of the knobs or by turning of keys in the locks. When one of the throw members 72, 73, or 74 is turned in either direction 65 it will engage with one of the wing members 145 and simultaneously retract the tongue plate 142, the sub-tongue 139 and the bolt 132. When the bolt 132 is retracted by pressure due 70 to the closing of the door, the slot 140 in the 75 sub-tongue allows retractile movement of the

bolt and sub-tongue without moving the tongue plate or turning the knobs thus saving wear on these parts. A compression spring 158 engages with a member 159 in the bolt member 132 and yieldingly urges said bolt member 132 outwardly. 5 The action of the spring 137 urges the bolt trip 134 into a position in which the catch member 136 is moved down into the path of a bolt blocking member 146 which is carried on a pin 147 and partially guided in the bracket 10. The pin 10 147 extends out through the side of the lock case and is positioned where it may engage a door jamb or plate 148 and be moved thereby into obstructing position relative to the catch member 136 of the bolt trip 134. A spring 150 exerts an 15 outward pressure on the pin 147 and blocking member 146. When a pull is exerted on the sub-tongue 139 the first movement produced by this pull will be a rocking movement of the bolt trip 134 which will move the catch member 136 out 20 of the path of the blocking member 146 after which, further retractile movement of the sub-tongue 139 will retract the bolt 132 into a position as shown in Fig. 7. If an attempt is made to press the bolt 132 back when the door is closed 25 and the blocking member 146 is in obstructing position the catch member 136 will engage the blocking member 146 as shown in Fig. 8, and block the retraction of said bolt. This is a safety feature which prevents opening of the lock by 30 insertion of a thin tool between the face plate 130 and the strike plate 151 of the lock. When the door is not fully closed the blocking member 146 will not be in obstructing position and the bolt 132 may be retracted by pressure, in the 35 usual way, as by the striking of said bolt against a strike plate in the closing of the door. For this reason the blocking member 146 does not interfere with the normal operation of the bolt 132. 40

One device may also be provided for locking the slide mechanism so that the thumb turn knobs can not be moved when the door is open and another device may lock the thumb turn knobs when the door is closed. In Fig. 9, I have shown 45 means which will lock either one or two slides and the thumb turn knobs which are connected therewith against operation when the door is closed. This means consists in the provision of a catch member 152 on the end of a locking slide 50 153 and in the provision of hook portion 154 on the blocking member 146, said hook portion engaging on one side of the catch member 152 when the locking slide is in retracted position as shown by full lines and on the other side of 55 the catch member when the locking slide is in locking position as shown by dotted lines. The hook portion 154 will be clear of the catch member 152 except when the blocking member is moved inwardly by the closing of the door. When 60 this slide and thumb turn locking means is used it is possible to move the thumb turn and locking slides freely when the door is open but they are both locked as soon as the pin 147 is moved inwardly by the closing of the door. This means 65 may be used in connection with two locking slides which are interconnected in the manner shown in Fig. 11. This condition may be desirable where thumb turn controlled means are provided for locking both the inside and the outside knob, or where only the outside knob is locked by a thumb turn on the inside of the door and there is danger of a person on the outside reaching the thumb turn through a transom or by breaking a glass in the door. 70 75

In Fig. 10, I have shown means for locking slide 155, and thereby locking a thumb turn which may be connected with said slide, when a door is open and when the blocking member 146 is in nonobstructing position. This means may comprise a catch member 156 on a locking slide 155, said catch member 156 being arranged to be engaged by a hook-like portion 157 on a blocking member 146 of modified form. When the pin of the blocking member 146 is allowed to move outwardly by reason of the door being open the hook-like portion 157 may engage with the catch member 156. This means for preventing operation of the thumb turn when the door is open may be used where the setting of a thumb turn on the inside of the door will prevent retraction of the bolt by the use of a key in the lock on the outside and may be desirable in hotel locks which are provided with locking slide means operated by a thumb turn on the inside and having a pin 93 positioned to enter the notch 111 in the lock controlled throw member 74. If the thumb turn is locked against movement by locking the slide 155 in retracted position when the door is open it prevents a person from inadvertently moving said thumb turn into a locked position, in which operation from the outside by a key is blocked, then closing the door from the outside and permitting the bolt to snap locked with the locking slide in locking engagement with the key operated throw member whereby the door can not be opened by a key from the outside. This feature is useful in hotel locks as it prevents guests from locking themselves out of their rooms so that they can not get in even though they have their key. In some instances hook member 157 shown in Fig. 10, may be wide enough to engage with suitable catch portions on two slides which are positioned side by side or it may drop back of the member 156 as indicated by dotted lines, Fig. 10, and lock said slide in the forward position.

A lock 22 may be provided in one or both knobs as hereinbefore described. When one lock 45 is used it may operate through a throw member 74 to retract the bolt 132. When two locks are used both may operate on the same throw member 74 as shown in Fig. 17, or each may operate independently through throw members 80 and 81, 50 as shown in Fig. 16. This provides means for the direct operation of the bolt by the lock or locks.

In Fig. 18, I have shown a cross section of a knob spindle 31 having the hereinbefore described 55 holes 92 therein for the usual locking function and further having other holes 160 positioned at an angle to the holes 92 whereby the said knob shank may be turned through an angle sufficient to fully retract the bolt 132 and then locked in a 60 position in which the bolt is held retracted by moving one of the locking slides so that a locking pin is projected into one of the holes 160. This makes it possible for a door which is used a great deal to be opened and closed without turning the knobs or moving the bolt at each opening and closing movement of the door thus saving much wear on the bolt.

The operation of the several units, embodied 70 in this lock has been set forth in the foregoing description and the general operation of the lock may be briefly summarized as follows:

The lock is adapted for installation in the usual manner on any door and the several parts of the lock may be varied to suit the requirements 75 of the installation. The knob shanks are locked

or unlocked by movement of the locking slides which movement either moves the locking pins into the holes in the knob shanks or withdraws said pins from said holes. These locking slides may be moved by the thumb turn knobs as illustrated in Figs. 1, 2, 11 and 22 or they may be moved by key controlled throw means of the type illustrated in Fig. 12, or of the type illustrated in Fig. 13, or a combination of the thumb knob and key controlled throw means may be used. Either one or two locking slides may be used and each slide may carry pins for locking either one knob shank or both knob shanks and may also carry a pin for locking a throw member which is controlled by the use of a key in a primary lock 15 mechanism. A primary lock mechanism may be provided in one knob or in two knobs or it may be entirely dispensed with and the lock controlled entirely by thumb turn knobs.

The control of the locking slides by the blocking member, as illustrated in Figs. 9 and 19 is an important feature of the invention as it affords a means for rendering the thumb turn members inoperative under certain conditions. The throw mechanism which interconnects the primary lock 25 and the lock spindle is also an important feature of the invention.

The foregoing description and accompanying drawings clearly disclose a preferred embodiment of my invention but it will be understood that 30 this disclosure is merely illustrative and such changes in the invention may be made as are fairly within the scope and spirit of the following claims.

I claim:

1. Slide means for use in lock mechanism having two rotatably mounted knob shanks, embodying two locking slides mounted for longitudinal movement, means on each of said locking slides positioned to engage with and lock a knob shank 40 when the locking slide is moved toward the knob shank, and a slide moving means connected with both of said slides and adapted to move the two slides simultaneously in opposite directions.

2. Slide means for use in lock mechanism having two rotatably mounted knob shanks, embodying two locking slides mounted for longitudinal movement, means on each of said locking slides positioned to engage with and lock a knob shank 50 when the locking slide is moved toward the knob shank, a slide moving means connected with both of said slides and adapted to move the two slides simultaneously in opposite directions, and thumb turn means connected with said slide moving means for operating the same.

3. Slide means for use in lock mechanism having two rotatably mounted knob shanks, embodying two locking slides mounted for longitudinal movement, means on each of said locking slides positioned to engage with and lock a knob shank 60 when the locking slide is moved toward the knob shank, slide moving means connected with both of said slides and adapted to move the two slides simultaneously in opposite directions, and key actuated means operatively connected with said 65 slide moving means for moving the same.

4. Slide means for use in lock mechanism having two rotatably mounted knob shanks, comprising two locking slides mounted for longitudinal movement, means on each of said locking slides 70 positioned to engage with and lock a knob shank when the locking slide is moved toward the knob shank, a throw member operatively connected with one of said locking slides, lock controlled means for oscillating said throw member in two 75

- directions, and lever means operatively connecting said two slides for compelling simultaneous longitudinal movement of said two slides in opposite directions.
5. Slide means for use in lock mechanism having two rotatably mounted knob shanks, comprising two locking slides mounted for longitudinal movement, means on each of said locking slides positioned to engage with and lock a knob shank
10. when the locking slide is moved toward the knob shank, a throw member having a neutral position, a lock controlled spindle for oscillating said throw member in both directions from the neutral position, two links each having one end connected with said throw member, and means providing lost motion connections between the other ends of said links and the respective locking slides, whereby the throw member can always return to an inoperative position without moving the locking slides after said locking slides have been
15. moved into locking position by oscillation of said throw member.
6. Slide means for use in lock mechanism having two rotatably mounted knob shanks, comprising two locking slides mounted for longitudinal movement, means on each of said locking slides positioned to engage with and lock a knob shank when the locking slide is moved toward the knob shank, a throw member having two arms extending in opposite directions, a lock controlled spindle for oscillating said throw member in two directions from a neutral position, lever means pivoted between said two locking slides and having two oppositely projecting arms engaging the respective slides whereby when one of said slides is moved in one direction the other slide will be moved in the opposite direction, and means on each locking slide positioned for engagement by one of the arms on said throw member.

FRANKLIN H. HARP. 20
